LOOP ANTENNA

Henri G. Busignies, Forest Hills, and Philip J. Vander Woude, Riverdale, N. Y., assignors to Federal Telephone and Radio Corporation, Newark, N. J., a corporation of Delaware

Application March 5, 1943, Serial No. 478,083

8 Claims. (Cl. 250—33)

1

This invention relates to improvements in loop antennas, and more particularly to loop antennas made from a shielded flexible cable.

An object of this invention is to provide a simple but strong and rigid loop antenna.

Another object of this invention is to provide a shielded loop antenna structure utilizing shielded cable.

Other objects and advantages of the present invention will become apparent from the following description of a preferred embodiment thereof, illustrated in the accompanying drawings wherein:

Fig. 1 is a vertical view partly in section, of the general antenna assembly in accordance with the present invention;

Fig. 2 is a top plan view of the general antenna assembly illustrated in Fig. 1;

Fig. 3 is an enlarged cross-sectional view of the upper portion of the loop antenna assembly;

Fig. 4 is an enlarged cross-sectional view of an adjustable loop support;

Fig. 5 is an enlarged cross-sectional view of a base for the antenna assembly;

Fig. 6 is an enlarged cross-sectional view of a preferred form of cable to be used for the loop.

An application of the use of flexible cable to form a loop antenna is generally illustrated by way of example in Figs. 1 and 2 in connection with a loop antenna, sense antenna and counterpoise arrangement more fully described in the co-pending applications of T. H. Clark, S. N. 478,081, filed March 5, 1943, and T. H. Clark—P. J. Vander Woude, S. N. 478,082, filed March 5, 1943. This antenna assembly may include a generally vertical supporting rod 10 from the midpoint of which extend four radial arms 12 spaced 90° relatively to one another and attached to the rod 10 by means of a suitable connector 13. The bottom of the supporting rod 10 is held in a strengthening support 14 which, in turn, is mounted upon a generally hemispherical base member 16. The latter, in turn, may be attached to the top of a ship mast indicated at 17. The four arms 12 may be interconnected by bracing bars 20 attached thereto by suitable clamping devices 22.

The crossed loop in accordance with the present invention is formed by two flexible shielded cables 24 and 26, the tops of which pass through a top mount 18, attached to the top of a supporting rod 10, the ends of which are fastened at the base member 16, and the central portions of which are held by fastening devices 28 on the ends of the respective arms 12. Above the top mount 18 is

2

fixed an insulating ring 29 which supports a metal cap 30 from which projects a plurality of counterpoise rods 32. These rods are spaced at 90° relatively to one another and, in accordance with the disclosure of the afore-mentioned T. H. Clark application, they may extend in a direction to bisect the angle between the crossed loops. A sense antenna 34 extends upwardly from an insulating disk 36 mounted on top of the cap 30.

10 The upper portion of the loop, and more particularly the manner in which it is fastened to the top mount 30 is more fully illustrated in Fig. 3. It will be seen from Figs. 1 and 3 that the top of the supporting rod 10 is provided with a flange 13, while the lower portion of the top mount 18 is provided with a comparable flange 40, adapted to be connected to the flange 38. An insulating ring 29 is attached to the top mount 18 by means such as bolts 44, while the cap 30 is mounted upon the ring 29 by similar means such as bolts 46.

The tops of the cables forming the two loops pass, as illustrated, through the top mount 18. In order to securely hold the loops in place and prevent a strain upon the top curved portions, the 15 loops are securely held in openings in this top mount. For this purpose the openings in the top mount 18 may be provided with a rubber or other insulating bushing 62 through which is passed a metal sleeve 66 which, in turn, encloses a rubber 20 sleeve 64 immediately surrounding and attached to be pressed against the cable 24. The sleeve 66 is formed with a collar 68 on one end, which presses against the inner end of the bushing 62, limiting movement of the sleeve 66 in the down- 25 ward direction, and is threaded on its outer end. A cap 71 screws over the threaded end of the sleeve 66 and, through a metal washer 74 presses tightly against the rubber sleeve 64, squeezed down upon the surface of the cable. As previously 30 stated, in accordance with the present invention, each loop is formed from a flexible shielded cable, the shield being formed by an outer steel braid 70. This steel braid is cut off just above the collar 68 and a ferrule 72 brazed to the braid, this ferrule 35 projecting over the end of the collar 68 and assisting in preventing downward strain upon the cable. As is common practice in shielded loop construction, the upper portion of each loop will be unshielded so that by removal of the braid 70 and 40 any inner braid, if used, the top of each loop will consist solely of insulated conductor 78. In Fig. 3 there may also be seen the end of the cable 26 which may pass over (or beneath) the unshielded portion 78 of the cable 24. In order to properly 45 attach the cable holding means in the top mount

55

and to firmly make connections within this top mount, the latter may be in a somewhat skeletonized form, being provided with a plurality of through working apertures 71.

In order to properly tension the flexible cable without, at the same time preventing strain upon the bends of the cable, we provide a special supporting bracket 28 on the ends of the cross arms 12. This bracket is illustrated in more detail in Fig. 4, and will be seen to have a generally Y-shape, the arms of the Y in this case lying in a generally vertical plane. The clamping means themselves may consist of half shell clamping sections 200, enclosing a rubber bushing 202 which closely surrounds straight portions of the loop and which is held to the bracket 28 by these clamping shields. The latter may be attached to the bracket proper by means such as screws 204. Ferrules 206 are soldered or brazed to the outer shield 70 on the cable 24, these ferrules being attached at the end of the curved portion of the loop to prevent strain upon such curved portion resulting from tension on the straight portions.

In order to tension the loop as a whole to form a rigid loop structure, means are provided for adjusting the position of the bracket 28 upon the end of the crossed arms 12. For this purpose the crossed arms 12 are preferably made hollow and in their hollow ends are mounted insulators 208 provided with two reduced sections, one having a pin opening 210 and adapted to fit into the end of the cross arm and the other having a pin opening 212 adapted to fit into sleeve 214. Pins through the openings 210 and 212 will respectively attach the insulator 208 to the cross arm 12 and the bracket 28, while at the same time separating these two parts. The sleeve 214 is adapted to be slidably mounted within a bore 216 in the bracket 28, relative rotation being prevented by a suitable keyway 218 in cooperation with adjustable key-engaging members 220. In accordance with the present invention one end of the sleeve 214 is closed but is provided with a threaded opening into which projects the end of a threaded shaft 222. On this shaft is a collar 226 which rests against a shoulder 228 of the bore 216. An extension 230 on the shaft 222 projects outwardly from the bracket 28 and is suitably shaped so that it may be engaged by an adjusting tool (not shown). The operation of the adjusting arrangement illustrated in Fig. 4 will be clear to those skilled in this art. Rotation of the shaft 222 will, through its reaction on sleeve 214 move the bracket 28 inwardly or outwardly, as desired, and will thus control the tension of the straight portions of the loops between the brackets and the top mount on the base. The straight portions of the loop may in this arrangement be made extremely rigid so that there will be no variations in the loop to effect the calculations of the direction finding system as a whole, while at the same time there will be no strain upon the curved portions of the loop since the tensioning points are formed by the clamp 200 on either side of said curved portion. It will be noted in this connection that the same condition holds true for the connection of the top of the loop in the top mount, which is due to the rigid connecting device illustrated. The strain caused by tensioning of the cable from the adjustable bracket 28 will be upon the connecting device at the top of the loop and not upon the top of the loop itself.

In Fig. 5 we have illustrated some details of a

base member upon which the loop antenna or the line antenna assembly may be mounted. This may consist of a generally hemispherical hollow casting 16 which will rest upon a suitable flange 138 on top of the mast 17. The seating gasket 139 is interposed between the castings 16 and the flange 138, and a tight connection may be made through means such as bolts 141. The sloping side of the castings 16 are formed by four spaced openings 144 to receive the ends of the loops 24 and 26. These loop ends must be rigidly attached to the base together to the loop structure and the connection may also be made water-tight. In accordance with the present invention, it is also made rigid; to effect such an arrangement, the openings 144 are provided on the outside with a circular internally threaded portion adapted to receive a collar 150 externally threaded at both ends. One end of the collar 150 is threaded into the openings 144 and presses against a grounding washer 148 which, in turn, presses against the end of a ferrule 146 brazed or otherwise attached to the braided shield 70 on the cable 24. Within the collar 150 is spaced a rubber sleeve 152 which tightly grips the surface of the cable and is pressed against the cable and externally against the collar 150 by means of a compression nut 154 threaded over the other end of the collar. This arrangement holds the cables tightly with respect to the base 16, but leaves the two ends of the loops free of strain so that they may be connected to appropriate terminal blocks 156. Similar holding means are, of course, used to hold the lower ends of the loop 26.

These terminal blocks 156 are preferably positioned around the bottom of the base 16 and are mounted in suitable openings therein and attached thereto by means such as screws 158 and 160. On the inner side of the terminal blocks 156 and held in place between another upon the screws 158 are clamps 162 which surround the shielded ends of the cable and rigidly hold them to the terminal block. Leads 164 extend from each screw 158 to a common central rod 166 passing from one side toward terminal block through to the other. A lead 168 on the outside of the terminal block connects the pin 166 to the shield 170 of a flexible cable 172 extending down and externally of the mast 17 to the radio equipment. The terminal blocks 156 are also provided with a pair of pins 174 to which are attached the ends of the loop conductors themselves. Between the pins 174 and a second pair of pins 178 positioned immediately below them are attached resistors 176 for the purpose of improving characteristics of the loop antenna as more clearly explained in a copending application of Dauvaras, S. N. 478,079, filed March 5, 1943. The lower pins 178, in turn, are attached through leads 180 to the dual wires of the cable 172. The various pins 166, 174 and 178 may be held in place in the terminal blocks by enlarged fluted portions 167. The details of this base structure are also more clearly explained and claimed in the aforementioned Clark-Vander Woude application.

The dual cables 172 forming the transmission line to the radio apparatus are held within the base 16 by means of rubber bushings 186 pressed about the end thereof and mounted on one side in a cup-shaped rubber 184 of each terminal block and held on the outside by covers 190 which are attached about the openings in the base 16 as by bolts 192. These covers at the same time serve

to protect the outer sides of the terminal blocks and in order to provide a water-tight connection suitable gaskets 194 may be interposed between each cover and the base.

The type of cable which has been used, by way of example, to form the shielded loop of the present invention is illustrated in cross-section in Fig. 6. As is there illustrated, such cable will preferably consist of an inner conductor 250 surrounded by two lines of insulation 252 and 254. About these two lines of insulation is a copper braid 256 which, in turn, is surrounded by another line of insulation 258. A steel braid 70 surrounds the entire cable and forms the shield thereof. While this form of cable has proven to be particularly adaptable for use to form a shielded loop antenna, it is to be clearly understood, of course, that the invention contemplates using any comparable shielded insulated flexible cable.

For the sake of clarity, the invention has been described in connection with certain specific apparatus, more particularly certain direction finding equipment but, it is to be understood that the particular structural details given have been presented by way of example and that the invention is not to be considered as limited thereto but only as set forth in the objects and the following claims.

We claim:

1. A loop antenna including, in combination, a framework having a base, a central vertical supporting rod projecting therefrom, cross arms extending radially outwardly from said vertical rod, and a shielded flexible cable attached at its top to the top of said rod, stretched over the ends of said cross arms and having its ends fixed to said base member.

2. The combination according to claim 1, in combination with spaced means on the top of said rod, firmly gripping the cable on either side of the top of said cable, and spaced means on the end of each cross arm, gripping the cable at two spaced points at either side of the corners of said cable, whereby said cable is firmly held in place without strain on its bent sections.

3. The combination according to claim 1, in combination with a Y-shaped bracket on the end

of each cross arm, and clamping means on the ends of the arms of each Y for gripping said cable to hold the same rigidly relative to the top of the supporting rod and to said base member respectively, without strain on that portion of the cable between the arms of each Y.

4. The combination according to claim 1, in combination with cable clamping means on the outer end of each cross arm, and means for radially adjusting the position of said clamping means.

5. A loop antenna including in combination, a framework having a base, a central vertical supporting rod projecting therefrom, cross arms extending radially outwardly from said vertical rod, a shielded flexible cable attached at its top to the top of said rod, stretched over the ends of said cross arms and having its ends fixed to said base member, a Y-shaped bracket on the end of each cross arm, means for radially adjusting each Y-shaped bracket, and clamping means on the ends of the arms of each Y for gripping the cable.

6. The combination according to claim 5, in combination with a pair of ferrules firmly attached to the shielding on that portion of said cable extending between the arms of the Y of each bracket and bearing against said clamping means.

7. The combination according to claim 5, in which said clamping means each include a rubber bushing tightly engaging the outer surface of the cable, and means for attaching said rubber bushings to the arms of each Y-shaped bracket.

8. The combination according to claim 5, in which each Y-shaped bracket is formed with a hollow bore in its base, in combination with an extension on each cross arm projecting into said bore, and in which said adjusting means includes a threaded shaft in said bore threadably engaging the extension on each cross arm, a collar on said shaft bearing against the end of said bore, and an extension on said shaft projecting from the base of said bracket and adapted to be turned for rotating said threaded shaft and varying the relative position of the bracket on the cross arm.

HENRI G. BUSIGNIES.
PHILIP J. VANDER WOUDE.
